MULTI-PLY BAG AND METHOD OF PRODUC-
ING THE SAMEEugene W. Sweeney, Brooklyn, N. Y., assignor to
Arkell Safety Bag Company, New York, N. Y., a
corporation of New York

Application September 12, 1931, Serial No. 562,435

9 Claims. (Cl. 150—9)

My invention relates to a multi-ply bag, and has special reference to such bags for holding cement and other finely divided material, and further relates to a method of producing the same.

5 One of the objects of my invention is to provide a novel and improved valve for a bag of this character, and method of producing the valve.

Another of the objects of my invention is to provide a valve for a bag which when closed effectively prevents sifting of the contents thereof.

Referring to the accompanying drawings,

Figure 1 is a plan view of a strip from which one form of my improved bag may be constructed;

15 Fig. 2 is a view in perspective of one end portion of a bag tube formed from the strip;

Fig. 3 is a sectional view on an enlarged scale taken on the line 3—3 of Fig. 2;

20 Fig. 4 is a side view of said end portion of the bag tube when flattened preparatory to forming a satchel end thereon;

Fig. 5 is a side view of one end of the completed bag;

25 Fig. 6 is a sectional view, on an enlarged scale, taken on the line 6—6 of Fig. 5;

Fig. 7 is a view in perspective of one end portion of a modified form;

30 Fig. 8 is a sectional view, on an enlarged scale, taken on the line 8—8 of Fig. 7.

My invention is illustrated in the drawings as embodied in a five-ply paper bag of the type of the one described and claimed in the patent to Bartlett Arkell, "Multi-ply bag and method of producing the same", No. 1,805,067, dated May

35 12, 1931. As shown, this bag is formed from a strip 2 of paper or other suitable material which is wound upon itself to form a cylindrical bag tube (Fig. 2), the several convolutions or plies of the tube being secured together by adhesive 6 suitably

40 applied to the strip previous to winding. When the tube has been thus formed, it is flattened on diametrically opposed lines 8. In Fig. 5, one end of the bag tube is shown closed by a satchel end comprising end flaps 10 and 12, and side flaps 14

45 and 16, the side flaps overlapping and being secured together and secured to the end flaps by adhesive in the usual manner.

To provide my improved valve in the bag, the strip 2, previously to winding, is provided with a 50 plurality of slits 18 which are arranged parallel to and spaced different distances from one of the longitudinal edges of the strip, and adhesive may be applied to one side of the strip substantially as shown.

55 The slits 18 are so arranged that in the com-

pleted bag tube shown, they extend across one of the edges of the flattened tube and are spaced apart from the slit which occurs in the outermost ply toward the end of the tube. The adhesive 6 is so applied as to secure the several plies together adjacent the ends of the slits on the lines 20, and to secure the portion of each ply to the rear of its slit to the superposed ply as indicated in Figs. 3 and 6. The slits are so positioned that in the satchel bottom they occur in the end flap 10 thereof.

With this construction of valve, it will be apparent that the filling nozzle for the bag may be inserted, first through the slit 18 in the outermost ply of the flap, then through the slit in the next 70 ply, then through the slit in the third ply and projected into the bag between the ends of the third and fourth plies. When the nozzle is withdrawn from the valve and the valve is closed by the pressure of the contents of the filled bag, it will be 75 apparent that there is no danger of any substantial sifting of the material through the valve during the handling of the bag. In effect, my improved valve is made up of a plurality of valve sections and they all cooperate to prevent sifting. 80 In case any material works through the first section it is shut off from further movement through the valve by the second section and so on, and by thus making the valve of a sufficient number of sections, depending on the nature of the material, 85 satisfactory results are secured. By pasting each ply adjacent the rear portion of its slit to the overlying ply, and the several plies together adjacent the ends of the slits, there is no danger of the nozzle catching on the walls of the slits, and the nozzle 90 may be easily inserted and removed.

In Figs. 7 and 8 of the drawings instead of the valve being shown in one of the end flaps of the satchel bottom, it is embodied in one of the side walls of the bag. In this form, the valve slits 22 95 in the three outermost plies may be arranged longitudinally of the bag, and sufficiently close to the top thereof as to permit the end of the nozzle to be positioned at a high enough level to effect substantial filling of the bag. In this form, the material of the outer ply about the slit therein may be reinforced by a piece 24 of fabric or other suitable material.

While my improved valve is particularly adapted for use in a satchel ended wound bag, it 105 obviously may be similarly incorporated in bags in which the plies are made up of separate sheets, whether the ends of the bag are closed by satchel ends, sewed seams or other means.

As will be evident to those skilled in the art, 110

my invention permits various modifications without departing from the spirit thereof or the scope of the appended claims.

What I claim is:

- 5 1. A multi-ply bag of the class described provided with a valve comprising openings in superposed plies respectively, successively arranged in spaced relation from the outer toward the inner end of the valve, said openings being so arranged 10 that in the insertion of a filling nozzle through the valve the nozzle may pass successively through said openings.
2. A multi-ply bag of the class described provided with a valve comprising openings in superposed plies respectively, successively arranged in spaced relation from the outer toward the inner end of the valve, with a portion of each ply adjacent the rear of its opening secured to the overlying ply.
- 15 3. A multi-ply bag of the class described provided with a valve comprising openings in superposed plies respectively, successively arranged in spaced relation from the outer toward the inner end of the valve, with a portion of each ply adjacent the rear of its opening secured to the overlying ply and the portions of the plies adjacent the sides of said openings secured together.
4. A multi-ply bag of the class described provided with a valve comprising slits in superposed 20 plies, respectively, arranged in parallel relation and successively spaced apart from the outer toward the inner end of the valve, said slits extending transversely of the valve whereby in the insertion of a filling nozzle through the valve the nozzle may pass successively through the openings provided by said slits.
5. A multi-ply bag of the class described provided with a valve comprising slits in superposed plies respectively, arranged in parallel relation 25 transversely of the valve and successively spaced apart from the outer toward the inner end of the valve with the portion of each ply adjacent the rear of its slit secured to the overlying ply and portions of the plies adjacent the ends of the slits 30 secured together.
6. A multi-ply bag of the class described provided with a satchel end and a valve in one of the end flaps of the satchel and comprising transverse slits in superposed plies respectively, arranged in parallel relation and successively spaced apart from the outer toward the inner end of the valve, the slit in the outer ply of the flap being arranged adjacent one end of the side flaps of the satchel end, whereby in the insertion of a filling nozzle through the valve, the nozzle may pass successively through the openings provided by said slits. 35
7. A multi-ply bag of the class described having a valve in one of its side walls comprising openings in superposed plies respectively, arranged successively in spaced relation from the outer toward the inner end of the valve, said openings extending transversely of the valve whereby in the insertion of a filling nozzle through the valve the nozzle may pass successively through said openings. 40
8. The method of making a bag of the type in which the bag tube is formed by winding a strip upon itself a plurality of times which comprises forming slits in the strip previously to winding, arranged parallel to and at different distances from one of the longitudinal edges of the strip and applying adhesive to the strip so that when the strip is wound up the slits in the several plies are successively spaced apart with the portion of each ply to the rear of its slit secured to the overlying ply and the portions of the slitted plies adjacent the ends of the slits secured together. 45
9. A multi-ply bag of the class described provided with a valve comprising valve openings in the several plies, respectively, said valve openings being spaced apart from the outer toward the inner end of the valve and the portions of the plies extending between said openings forming the wall of the valve, whereby in the insertion of a filling nozzle through the valve the nozzle may pass successively through said openings. 50
